UNITED STATES PATENT OFFICE.

OSCAR F. MOSSBERG, OF HATFIELD, MASSACHUSETTS.

REPEATING FIREARM.

SPECIFICATION forming part of Letters Patent No. 651,577, dated June 12, 1900.

Application filed February 19, 1900. Serial No. 5,680. (No model.)

To all whom it may concern:

Be it known that I, OSCAR F. MOSSBERG, a citizen of the United States of America, residing at Hatfield, in the county of Hampshire and State of Massachusetts, have invented new and useful Improvements in Repeating Firearms, of which the following is a specification.

This invention relates to repeating firearms, and is particularly directed to the improvement of an arm of the class in which the magazine is located parallel with the barrel.

One object of the invention is to produce an arm in which the movement of the trigger in one direction will actuate devices for bringing a cartridge from the magazine into line with and in firing position in the barrel and cock and fire the arm.

A further object lies in the improved construction of the arm whereby the firing mechanism may be locked independently of the trigger and the latter operated to eject cartridges from the magazine without danger of accidental explosion, in improved means for ejecting the shell of a cartridge through the side-plate of the arm, in devices for locking the sliding barrel in firing position, and in other improvements in construction, all as will be fully set forth in the following specification and pointed out in the claims.

In the drawings forming part of this specification, Figure 1 is an enlarged side elevation of the arm embodying this invention, the side plate being removed and the magazine empty. Fig. 2 shows the position of the parts of the arm when ready for loading. Fig. 3 is a longitudinal section of the arm in the position the parts occupy at the beginning of the cocking and firing movement of the trigger.

Fig. 4 shows the position of the same parts as the firing-pin is about to be released at the termination of the firing movement. Fig. 5 is a perspective view of one of the side plates of the arm and shows the breech-block, ejector, carrier for moving cartridges from the magazine into axial alinement with the barrel, and the sliding door closing the opening through which the magazine is charged and the lock for said door. Fig. 6 is a top plan view taken about on section-line 6 6, Fig. 1. Fig. 7 is a transverse section on line 7 7, Fig. 1, and illustrates principally the ejector de-

vices. Fig. 8 is a perspective view of the inner side of the right-hand plate through which the ejection of the cartridges is effected. 55

Briefly stated, the novel features of construction embodied in this arm consist in a magazine located above the barrel and in the same vertical plane, a sliding barrel to which the trigger is attached, a cartridge-carrier 60 moving in a vertical plane raised into cartridge-receiving position relative to the magazine by the rearward movement of the barrel and actuated in a reverse direction by a spring to carry a cartridge after the barrel has moved 65 forward down into position to be engaged by the latter during its next rearward movement, of a firing-pin having a longitudinal movement in a breech-block and engaged by a member on the rearward extension of the barrel when 70 the latter moves rearwardly, whereby a spring is compressed, which is released when the barrel has attained its rearmost position, permitting the firing-pin to shoot forward against the cartridge-primer and discharge the arm, 75 suitable devices, to be described farther on, for locking the barrel in fixed firing position, and suitable safety devices for locking and preventing the actuation of the firing-pin, if desired, when the barrel is moved rearwardly. The top of the arm is provided with 80 an opening for giving access to the rear end of the magazine for charging the latter, and a sliding door closes said opening during the firing of the arm. 85

Referring to the drawings, 1 is the frame of the arm, and 2 is the sliding barrel, which has a sliding movement in a cylindrical portion 3 of the frame. The rear end of the barrel is rectangular in cross-section, and the forward end of said rectangular portion forms a shoulder 4, which abuts against the frame, as seen in Fig. 1 of the drawings, and limits its movement in a forward direction, and the rear end of said rectangular portion is 90 squared off vertically and abuts against the forward end of the breech-block 5 and limits the rearward movement of the barrel. From said rectangular portion of the barrel there is an extension of the barrel rearwardly 95 in a lower plane and indicated by 6, in which the trigger 7 is hung on a pin 8 and which extension also receives the parts operating the firing-pin, to be described farther on. 100

The trigger 7, connected directly with the barrel, serves to draw the latter rearwardly, and this movement compresses a coiled spring 9, supported in the line of movement of said barrel partly by the tube 10 and partly by the pin 11, pivotally connected to the extreme rear end of said barrel extension 6. The end of said pin connected with the barrel extension is squared and forms a shoulder 10 for one end of the spring 9, and the free end of a flat spring 12 (see Figs. 3 and 4) is supported between this squared end of said pin and a pin 13, fixed in the side plate, and has its opposite end secured to the trigger 7. The 15 spring 12 is adapted to yield only at the termination of the compression of the spring 9—that is, when the barrel has been forced rearwardly to its fullest extent. To insure the full rearward movement of the barrel before 20 the trigger can be oscillated on its pivot, said trigger is provided with a forwardly-projecting arm 14, which during the rearward movement of the barrel slides along the frame and at the termination of said movement serves 25 as a lock for the barrel, whereby it is held firmly against the breech-block, as will be described farther on. The same effect would be attained if the spring 12 were of such strength as to yield only under a force superior 30 to that required to compress the springs 9 and the firing-pin spring, (to be referred to farther on.) The above-referred-to forwardly-projecting arm 14 of the trigger is provided with a solid block 15 on its extremity that 35 serves as a lock for the barrel when the latter has reached its firing position—that is, when it abuts against the end of the breech-block—and this block is brought into position to effect this locking of the barrel by the continued pull on the trigger after the barrel has 40 come to a stop. This continued pull, as aforesaid, causes the trigger to swing on its pivot-pin, and swings the arm 14 downward and interposes the block 15 between the 45 squared shoulder 16 on the barrel and the shoulder 17 on the frame of the arm.

The movement of the trigger above referred to, which serves to lock the barrel, also imparts movement to the device which releases the firing-pin; but the actuation of the last-named device is timed to follow the locking of the barrel, and thus insures the arm against accidental explosions before the locking of the barrel has been effected. Before describing the said firing-pin-releasing devices it will be in order to describe the firing-pin. The latter is indicated by 18 and is axially located in the breech-block 5. It is cylindrical in cross-section and is provided at its rear end 50 with a depending lug 19, which lies in a slot 20 in the underside of the breech-block, said lug projecting beyond the surface of the block far enough to be engaged by the end of the sear 21, which is pivoted in the extension 6 of the barrel, the forward end of said lug being squared off to receive the end of said sear 21 when the barrel is rearwardly drawn by the

trigger. Said firing-pin is bored out from its rear end forward to receive one end of its actuating-spring 22, whose opposite end is supported on a pin in the frame of the arm. The forward end of the firing-pin is reduced and extends axially from the body thereof through the end of the breech-block in the usual manner to a sufficient extent to reach the primer in the head of the cartridge and explode it. 70

The sear 21 is supported, as stated, in the extension of the barrel on a pin 23 and is provided with a coiled spring 24, (see Figs. 3 and 4,) whereby the rear end of said sear is forced upwardly into the path of movement of the lug 19 and whose opposite end is held in contact with the upper end of the trigger, as shown in the drawings. When the trigger is operated to draw back the barrel and the 80 spring 12 remains slack, the rear end of the sear 21 will engage the lug 19, as shown in Fig. 3, and remain in this position until the position shown in Fig. 4 is reached. This is just prior to the release of the firing-pin. At this stage of the movement of the trigger continued pull on the latter first causes the arm 14 to swing down and interpose the block 15 thereon between the barrel and frame, as described, and simultaneously to raise the forward end of the sear, whereby its rear end is disengaged from the lug 19 on the firing-pin 95 18 at the moment the block 15 has reached its proper locking position, and thus at the moment of discharge the breech-block, barrel, and frame of the firearm become practically one piece. When pull on the trigger is released, the spring 12 returns it to normal position, as seen in Fig. 1 and 3, (Fig. 2 showing the position of the parts at the moment of discharge,) and as said trigger returns to normal position the spring 24 causes the sear 21 to also return to its normal position, and as the barrel is forced forward again by its spring 9 the rear end of said sear will ride over the lug 19 and be snapped up in front of said lug ready for a return cocking movement. 100

The method of effecting the ejection of the empty shell will be described after a description of the magazine and the cartridge-carrier. Said magazine comprises a tube 25, located over and in the same vertical plane as the barrel and may be integral with the frame, as shown herein, or may be made as a separate piece and secured in the frame. Within the magazine is a coiled spring 26, adapted to be compressed by the insertion of cartridges into its open rear end, said spring serving to push the cartridges rearwardly, as usual in this form of magazine. The tube 25 is charged by opening the door 27, which has a sliding movement on the top of the breech-block 5. It is guided in its sliding movement by engagement with a groove 28 in one of the side plates, a part of which shows in Figs. 5 and 7. It is seen also in dotted lines in Fig. 3. Said door is provided with a spring 29 in a groove in the under 110 120 130 140 150

side thereof, which is compressed when the door is shut and which opens it when its locking-bolt 30 is operated. This bolt is seen in Figs. 1, 2, 3, 5, and 7 most clearly, 5 and extends transversely through the left-hand side plate and the breech-block 5, its outer end having a button and its inner end a short upstanding arm 31, which when the door is shut engages a slot 32 in the side 10 thereof, being brought into engagement therewith by a spiral spring about the body of the bolt in the breech-block 5, but shown in the drawings in Fig. 7 only. One end of said bolt 30 is squared, as seen in Figs. 5 and 15 7, to prevent its turning on its axis, and whereby the arm 31 is adapted to act as a stop for limiting the rearward movement of the door by means of the pin 33, which contacts therewith. (See Fig. 5.) To permit 20 endwise movement to said bolt, the right-hand side plate is cut away opposite the arm 31, as shown in Fig. 7.

The cartridge-carrier 34 is a vertically-sliding member positively operated by the 25 barrel upwardly and forced down by a spring 35, interposed between the top of the carrier and the top wall of the frame. This carrier 34 is seen most clearly in Fig. 5 in perspective. When it is forced upward by the 30 barrel, it arrives at a position for receiving a cartridge from the magazine, and when it is in this position the top of the squared end of the barrel closes the under side of the cartridge-carrier, the cartridge resting on the 35 top of the aforesaid part of the barrel. The end of the door 27, which is in the same vertical plane as the forward end of the breech-block 5, forms a stop for arresting the rearward movement of the cartridge. The carrier 40 is held in its uppermost position by a hooked lever 36, pivoted to the frame, and which is allowed to swing under the edge of the carrier by the rearward movement of the barrel, as seen in Fig. 2, and when the barrel 45 moves forward after the discharge of the firearm the said lever is disengaged therefrom by a pin 37 in the barrel, and thus releases the carrier, which will then be forced down by its spring and carry a cartridge 50 down into the position shown in Fig. 3, axially in line with the barrel. As the cartridge descends, the rim of the head thereof enters the vertical groove 38 on the right-hand side of the forward end of the breech-block, which 55 serves as a hook to hold the shell in ejecting position when the barrel moves forward after the discharge, the ejector 39 being located in a groove in the left-hand side of the breech-block 5, between it and the left-hand side 60 plate. Said cartridge-carrier comprises one side plate 34^a, which has a sliding movement in an undercut groove in the left-hand side plate, as shown in Figs. 5 and 6, and the smaller opposite side plate 34^b of the carrier 65 is supported in parallel relation with said first-named plate 34^a by the top plate 34^c, thus constituting a rectangular construction com-

posed of two sides and a top. The forward end of the top plate 34^c is turned up at right angles thereto and is of sufficient length to 70 extend up into the path of movement of the cartridge, as shown in Fig. 3, when the carrier has been forced downward to carry a cartridge to the loading position, thus forming a cut-off for the magazine without which the 75 cartridges would, when the carrier is down to the position shown in Fig. 3, shoot out of the magazine and block the ascent of the carrier. The latter is operated by the movement of the barrel by means of a projection 40 on the 80 side of the barrel, (shown only in dotted lines in Fig. 4,) which engages the inclined edge 41 of the side plate 34^a of the carrier. The opposite side 34^b of the carrier serves to retain the cartridge in position of alinement 85 with the barrel and serves also to cover the ejecting-opening 42 in the side plate (shown in Fig. 8) when the carrier descends and to uncover said opening when it ascends. Said right-hand side plate (shown in Fig. 8) is provided with an outwardly-swinging door 43, in 90 which is located the opening 42. Access may be had to the cartridge-carrier, the end of the breech-block, and the breech of the barrel through this door without removing the side 95 plate.

The ejector 39 is shown in perspective in Fig. 5 and in plan in Fig. 6 of the drawings and in dotted lines in Figs. 3 and 4. It consists of a flat spring the operative end of 100 which is divided into two fingers 44 and 45. The finger 44 is straight and the finger 45 is curved inwardly toward the axis of the barrel. The side of the breech-block opposite which the finger 45 lies is cut away, as shown 105 in Fig. 6 at 46, to permit lateral movement to said finger 45. The ejector is movable endwise as one piece in a suitable groove in the side of the breech-block 5, as stated, the rear end of said ejector being turned down, as at 110 47, Figs. 3 and 5, at right angles to the length of the part, whereby the end of the ejector is given a broader bearing in the groove in which it slides and is less liable to bind in its movements under any lateral strain brought 115 upon it by the straightening out of the curve of the finger 45, which occurs as follows: When a cartridge is brought down from the magazine, the fingers 44 45 occupy the position shown in Fig. 6, and when the barrel is 120 drawn back the side of the squared rear end thereof strikes the end of the finger 44, which is a trifle longer than the finger 45, and pushes the ejector back into its groove, compressing the spring 48 behind it. As the ejector moves 125 rearwardly the curved finger straightens out by sliding over the head of the cartridge, and by the time the barrel comes to a bearing on the breech-block the notch 49 in the end of the finger 45 snaps over the rim of the cartridge and remains in this position until the 130 arm is discharged. Then as the barrel moves forward the shell remains stationary, held by the hook on the end of the breech-block until

the barrel is disengaged therefrom, and at the same instant and by the same movement the carrier is released and flies upward, and thus uncovers the opening 42, through which 5 the shell is ejected by the simultaneous movement of the ejector forward and by the retraction of the curved end of the finger 45, which had been put under tension by being forced backward over the rim of the cartridge.

10 The action of the ejector is made more certain as to the direction of movement of the shell by the engagement of the latter with said groove 38 on the side of the breech-block 5, as the said hook acts as a pivot on which 15 said shell is turned by the pressure brought to bear on it by the ejector in a line diagonal to its axis.

The end of the breech-block 5 is provided with an annular depression 50, into which 20 the head of the cartridge-shell is pushed when engaged by the barrel. The object of this 25 recess is to take the end of the firing-pin out of the line of movement of the head of the cartridge as the latter moves down from the magazine to the barrel.

25 A device for preventing the actuation of the firing-pin by the movement of the trigger and barrel consists in a sliding plate 51. (Shown particularly in Figs. 1 and 5, and a part of it 30 in section in Fig. 7.) This plate slides in a groove in the left-hand side plate and has a projection 52 on the inner end thereof, which is inclined on one edge thereof, and this inclined edge comes in contact with a pin 53 on 35 the sear and depresses the rear end thereof to an extent sufficient to cause said sear to fail to connect with the lug 19 on the firing-pin, and the trigger may then be manipulated at will without actuating the firing-pin. The 40 position of safety is shown in Fig. 1.

To load the magazine, the door 27 is unlocked and allowed to spring out to the position shown in Fig. 2. The safety-catch is set, as in Fig. 1. Then the trigger is drawn 45 back to raise the carrier, and the cartridges are then inserted, the last one remaining in the position of the one shown in Fig. 2, back of the carrier. The door 27 is then pushed forward until it locks, and this movement 50 carries the last cartridge into the carrier. The trigger is then released, and this cartridge is carried down into position to be engaged by the barrel, as seen in Fig. 3.

To empty the magazine, the bar 54, which 55 lies in a groove on top of the breech-block 5 flush with its upper surface and pivoted by its forward end near the end of the breech-block, is after the door 27 has been opened raised to the position indicated in dotted lines 60 in Fig. 2, whereby an inclined plane is provided for the support of the cartridges when they are ejected from the magazine by the action of the spring therein after the safety-catch has been set and the trigger then pulled 65 back and held in that position. Said bar 54 is raised by a pin 55, which projects through the side plate.

In order to provide for the proper alignment of the cartridge relative to the barrel laterally, the two bosses 56 and 57 are formed on the sides of the carrier, as shown in Figs. 5 and 6. These do not interfere with the free rearward movement of the barrel, as the carrier rises in time to remove them from the path of said barrel.

Having thus described my invention, what I claim, and desire to secure by Letters Patent of the United States, is—

1. In a magazine-firearm, a longitudinally-sliding barrel, a fixed breech-block, a firing-pin in said block movable axially relative to the barrel, a magazine in the same vertical plane as the barrel, a cartridge-carrier adapted to be actuated by the barrel to move in a vertical plane, alternately, between the end 80 of the magazine and the rear end of the barrel, means on the barrel for engaging the firing-pin when the barrel is moved rearwardly, a trigger for moving the barrel, and adapted to release the firing-pin at the end of the rearward movement of the barrel, substantially as described.

2. In a magazine-firearm, a longitudinally-movable barrel, a spring for moving the barrel in one direction, a trigger pivotally secured to the barrel for moving it in the opposite direction; a firing-pin, and devices on the barrel for moving the firing-pin into cocked position by the movement of the barrel and trigger, and for releasing said firing-pin at the end of said barrel movement, combined with a magazine and a cartridge-carrier adapted to move cartridges from said magazine into position to be engaged by said barrel, and a device for locking said barrel, im- 100 movably, at the moment of the release of the firing-pin, substantially as described.

3. In a magazine-firearm, a longitudinally-movable barrel, a trigger for imparting said movements thereto, said trigger being pivotally attached to said barrel, a barrel-spring adapted to be compressed by the movement of the barrel in one direction, a second spring for actuating the trigger, and means whereby said trigger is held in fixed relation to the barrel during the compression of the barrel-spring; a firing-pin and actuating devices therefor, adapted to be operated to release the firing-pin by the movement of the trigger after the compression of the barrel-spring, combined with a magazine and means for feeding cartridges from the latter into position to be engaged by the movement of the barrel by the trigger, substantially as described.

4. In a magazine-firearm, a magazine, a cartridge-feeding spring therein, a cartridge-carrier, a longitudinally-moving barrel, and means interposed between the barrel and carrier whereby the latter is adapted to move a cartridge from the magazine into position to be engaged by the barrel when the latter is moved rearwardly, a fixed breech-block against which the cartridge and barrel abut

when in firing position, means for immovably holding said barrel against the breech-block at the moment of discharge of the arm, a firing-pin in the breech-block, and firing-pin actuating devices attached to the barrel, and means for moving the barrel, substantially as described.

5. In a magazine-firearm, a frame, a magazine, a longitudinally-movable barrel, a cartridge-carrier supported in the frame, and means of connection between said carrier and the barrel, whereby the movement of the latter in one direction will effect the movement of the carrier in a line at right angles to that of the barrel; a supporting device for holding said carrier in a fixed position during the movement of the barrel in the opposite direction, and means on the barrel for releasing said carrier from said supporting device 20 at the end of the last-named barrel movement, whereby the carrier is adapted to place a cartridge in position to be engaged by the barrel, substantially as described.

6. The combination with the frame of a magazine-firearm, of a longitudinally-movable barrel, a magazine located in the same vertical plane as the barrel, a vertically-movable cartridge-carrier adapted to be raised by the rearward movement of the barrel, a spring 25 for moving it downward, at the end of the forward movement of the barrel, a door through which the magazine may be charged; an opening in the side of the arm adapted to be closed by the downward movement of the 30 carrier, and uncovered when the latter moves upward, whereby the ejection of a shell is permitted; a firing-pin, and devices for actuating the latter by the movement of the barrel, and an ejector for the cartridge-shells, 35 substantially as described.

7. In a magazine-firearm, a longitudinally-sliding barrel, a suitable magazine and devices for transferring a cartridge therefrom into position to be engaged by said barrel on its rearward movement, a trigger for moving said barrel rearwardly, a barrel-spring for moving it in the opposite direction, a trigger-spring, a barrel-locking device actuated by the trigger at the limit of rearward movement 45 of the barrel, a firing-pin, and actuating devices therefor attached to the barrel and adapted to be operated to release the firing-pin after the operation of the barrel-locking mechanism, substantially as described.

55 8. In a magazine-firearm, a longitudinally-

sliding barrel, a magazine, a cartridge-carrier having a transverse sliding movement relative to the rear end of the barrel, a portion of said carrier lying alongside of said barrel; an incline on said last-named portion 60 of the carrier, a stud on the barrel engaging said incline whereby the rearward movement of the barrel will move said carrier in one direction, and a spring adapted to move said carrier in the opposite direction, substantially 65 as described.

9. In a magazine-firearm, a longitudinally-sliding barrel, a magazine, a sliding cartridge-carrier adapted to move transversely from the end of the barrel to the end of the magazine, means of connection between said barrel and carrier, consisting of an inclined plane on one of said parts and a stud on the other engaging therewith whereby the latter is moved toward the magazine by the rearward movement of the barrel; a spring for 70 moving the carrier from the magazine toward the end of the barrel, and a magazine cut-off on the carrier, whereby when the latter is located opposite the end of the barrel the cartridges will be retained in the magazine, substantially as described.

10. In a magazine-firearm, a frame, a magazine, a sliding door in the frame through which cartridges are inserted in the magazine, a 85 transversely-movable cartridge-carrier between said door and said magazine, a shoulder on the forward end of the door adapted to retain the rearmost cartridge in the arm and to force it into said carrier, when the door is closed, substantially as described.

11. In a magazine-firearm, a frame, a magazine and a spring therein, a sliding-door movable axially relative to the magazine, a transversely-movable cartridge-carrier between 95 said magazine and said door, a shoulder on the forward end of the door adapted to retain the rearmost cartridge in the arm against the pressure of the magazine-spring, and a lever in front of said shoulder on said door 100 adapted to form an inclined plane from the under side of the cartridges in the arm to the top of said shoulder, whereby said magazine-spring may eject cartridges in the magazine through said door, substantially as described. 105
